Primary Examiner — T. Chase Nelson*Assistant Examiner* — Eric Goodman(74) *Attorney, Agent, or Firm* — Dickinson Wright PLLC(57) **CLAIM**

The ornamental design for a urinal seal, as shown and described.

DESCRIPTION

This design patent application is related to Design patent applications bearing Ser. Nos.: 29/353,286, 29/353,290, and 29/353,294 and also Utility patent application bearing Ser. No. 12/683,331 which are filed on even date herewith.

FIG. 1 is a rear perspective view of a urinal seal;

FIG. 2 is a side view thereof;

FIG. 3 is a top view thereof;

FIG. 4 is a bottom view thereof;

FIG. 5 is a rear perspective view of a urinal seal;

FIG. 6 is a side view thereof;

FIG. 7 is a top view thereof;

FIG. 8 is a bottom view thereof;

FIG. 9 is a cross section view along Line 9-9, as shown in FIG. 6 thereof;

FIG. 10 is a rear perspective view of a urinal seal;

FIG. 11 is a side view thereof;

FIG. 12 is a top view thereof;

FIG. 13 is a rear view thereof;

FIG. 14 is a cross section view along Line 14-14 as shown in FIG. 11 thereof;

FIG. 15 is a rear perspective of a urinal seal;

FIG. 16 is a side view thereof;

FIG. 17 is a top view thereof;

FIG. 18 is a rear view thereof; and,

FIG. 19 is a cross section view along Line 19-19 as shown in FIG. 16 thereof.
